ELECTRIC INHALER

George Schmahl, 1033 S. Westlake, Los Angeles, Calif.

Filed Feb. 6, 1961, Ser. No. 63,841

Term of patent 14 years

(Cl. D83—1)

FIG. 1 is a front elevational view of the electric inhaler embodying my new design;

FIG. 2 is a side elevational view thereof taken from the right of FIG. 1;

FIG. 3 is a rear elevational view thereof;

FIG. 4 is a side elevational view thereof taken from the left of FIG. 1;

FIG. 5 is an elevational view thereof taken from the top right of FIG. 2; and

FIG. 6 is a bottom plan view thereof.

I claim:

The new and ornamental design for an electric inhaler, as shown.
